UNITED STATES PATENT OFFICE.

PETER W. MURPHY, OF DETROIT, MICHIGAN, ASSIGNOR TO THE MURPHY ENGINEERING COMPANY, OF DETROIT, MICHIGAN, A CORPORATION OF MICHIGAN.

GUIDEWAY AND SLIDING MEMBER THEREFOR.

1,348,371.

Specification of Letters Patent.

Patented Aug. 3, 1920.

Application filed May 27, 1918. Serial No. 236,754.

To all whom it may concern:

Be it known that I, PETER W. MURPHY, a citizen of the United States, residing at Detroit, county of Wayne, State of Michigan, have invented a certain new and useful Improvement in Guideways and Sliding Members Therefor, and declare the following to be a full, clear, and exact description of the same, such as will enable others skilled in the art to which it pertains to make and use the same, reference being had to the accompanying drawings, which form a part of this specification.

This invention relates to guideways and sliding members therefor, as for instance yokes for pistons of a multiple cylinder type of engine in which the cylinders are arranged in a circle with the longitudinal axes in parallel relation with a central shaft provided with a cam adapted to be rotated by reciprocation of pistons in the cylinders. A particular object of the invention is to provide a solid and substantial guideway for a sliding member that is of long life; that may be formed in the supporting body dispensing with the usual attachable side members and adapted to rigidly hold the member to reciprocal movement without possibility of lateral displacement. The general objects and the several novel features of the invention are hereinafter more fully described and claimed and shown in the accompanying drawings in which—

Figure 1 is a view partly in section showing my improved guideway and slide in use in an engine of multi-cylinder type.

Fig. 2 is a cross section on line $x-x$ of Fig. 1 showing the supporting case and mode of forming the guideways therein.

Fig. 3 is a detail of the slide having the form of a yoke and showing the conoidal rollers engaging the cam and mode of attaching the piston rods thereto.

This character of guideway and member traveling therein may be used in a variety of mechanisms wherein it is desired to hold the reciprocated part fixedly to a definite line of movement without possibility of lateral displacement and in which it is desired to dispense with the usual attachable guide members.

Heretofore it has been the practice to form a guideway one side of which is pro-

vided by an attachable part undercut to correspond with the opposite side member and in practice I have found that if excessive side strains are imposed on the sliding member the said attached part tends to loosen allowing lateral displacement of the side member which becomes noisy in operation and in fact detrimental to efficient operation of the parts.

In the accompanying drawings I have shown one type of mechanism with which this character of guideway and sliding member may be utilized. The device shown is a multi-cylinder engine having a series of cylinders 1 arranged in a circle about a center with the longitudinal axis of the cylinders parallel with the axis about which they are positioned and on which axis is positioned a drive shaft 2. On this shaft 2 is a cam 3 positioned forward on the inner ends of the cylinder and by means of which the power of the cylinder is applied to the shaft to rotate the same. Although not here shown there are two sets of cylinders at opposite ends of the cam, the pistons in directly opposite cylinders of the sets being connected to a yoke 4 which yoke carries the conoidal rollers 5 engaging opposite sides of the cam 3. The opposing cylinder castings are connected by a central cylindrical casting 6 which incloses the cam member and this central casting is formed with a series of cylindrical longitudinally extending grooves 7, the grooves being formed and extend from one end of the casting to the other opening through the said ends. These grooves, as will be understood from Fig. 2, are arranged in pairs, there being two grooves for each pair of opposed cylinders. In these grooves is the sliding member 4 the body of which is formed of two semi-circular portions 9 and 10 connected together and rising from the cylindrical portion as a base are the two standards 11 and 12 on opposite ends providing supports for the conoidal rollers 5 as shown in Fig. 3. Each pair of grooves 7 open into the central portion of the chamber, the wall of which is cut out as indicated at 14 to allow the standards 11 and 12 to extend into the chamber and be moved longitudinally thereof, the opening 14 in the arrangement here shown being on the axis of opposed cylinders at

opposite ends of the casting 6 and the width of the opening 14 being slightly greater than the width of the standards 11 or 12.

By the arrangement described with the 5 two circular portions 9 and 10 riding in each pair of grooves 7 (which grooves are greater than a half circle in form providing a central portion 15 extending centrally into the slide between the cylindrical portions there- 10 of) there is no possibility of the slide rocking in the support or moving laterally relative to the axis of the cylinders thus providing a very solid and secure support for the slide and dispensing with the usual at- 15 tachable parts as heretofore stated. These grooves being cut or formed in the casting and opening through the end members the slide members may be introduced into the grooves at the end. The opposite ends 20 of the slide are provided with bosses 16 and 17 preferably threaded to receive the piston rods of the pistons in the opposed cylinders companion thereto.

No attempt is here made to show the va- 25 rious operating parts of the engine, it being sufficient so far as disclosure of this invention is concerned to state that the opposing pistons are fixedly connected together by means of this yoke or slide and by rea- 30 son of the explosions alternately in oppo- site cylinders the yoke is made to recipro- cate in the guideway and by reason of the engagement of the rollers with the cam rotation of the central shaft is produced. By 35 force applied to one piston for instance there is a tendency for the yoke to move sidewise due to the form of the cam and this slide and guideway is devised to securely hold the yoke and prevent any lateral displace- 40 ment.

While I have shown the conoidal rollers carried by the yoke or slide 8, they are here shown to illustrate a slide member in which a side pressure is exerted during longitudinal 45 movement of the slide member in the way, it being understood that the said slide and

guideway therefor may be used with various constructions, as cross heads and the like, within the spirit of this invention.

What I claim is—

50

1. A piston rod supporting slide and guideway therefor comprising a slidable member having two connected cylindrical portions with a central depression between them, and a slideway comprising two semi- 55 circular grooves adapted to fit said cylindrical portions and having a central portion which extends into said central depression between the cylindrical portions of the slide.

2. A device of the character described 60 comprising a guideway having two substantially semicircular grooves separated by a central projecting portion, and a piston rod supporting member having two connected cylindrical portions with a central depression 65 between them adapted to accommodate said projecting portion, said slide supporting a pair of conoidal rollers adapted to engage a cam for rotating the cam as the member reciprocates in said guideway.

70

3. A piston rod supporting slide and guideway therefor comprising a slidable member having two connected portions with a central depression between them, and a slideway comprising two grooves adapted to 75 fit said portions and having a central portion which extends into said central depression between the portions of the slide.

4. A device of the character described 80 comprising a guideway having two grooves separated by a central projecting portion, and a piston rod supporting member having two connected portions with a central depression between them adapted to accommodate said projecting portion, said slide 85 supporting a pair of conoidal rollers adapted to engage a cam for rotating the cam as the piston rod supporting member recipro- cates in said guideway.

In testimony whereof, I sign this specifica- 90 tion.

PETER W. MURPHY.
